CLAIM

The ornamental design for a semiconductor module, as shown and described.

DESCRIPTION

FIG. 1 is a perspective view of semiconductor module showing my new design;

FIG. 2 is a top view thereof;

FIG. 3 is a bottom view thereof;

FIG. 4 is a front view thereof;

FIG. 5 is a rear view thereof;

FIG. 6 is a right-side view thereof; and,

FIG. 7 is a left-side view thereof.
